UNITED STATES PATENT OFFICE.

CHARLES R. CURRENT, OF DANVILLE, ILLINOIS.

COLLAR ATTACHMENT.

No. 911,295.

Specification of Letters Patent.

Patented Feb. 2, 1909.

Application filed January 10, 1908. Serial No. 410,271.

To all whom it may concern:

Be it known that I, CHARLES R. CURRENT, a citizen of the United States, residing at Danville, in the county of Vermilion and State of Illinois, have invented certain new and useful Improvements in Collar Attachments, of which the following is a specification.

This invention contemplates certain new and useful improvements in harness and the object of the invention is an improved collar attachment which is designed to be applied to the collar to raise the latter sufficiently to prevent the withers from resting 10 on the horse's neck and chafing the same, or to enable a sore already formed on the neck to heal.

With this and other objects in view that will more fully appear as the description 20 proceeds, the invention consists in certain constructions and arrangements of parts that I shall hereinafter fully describe and claim.

For a full understanding of the invention and the merits thereof, reference is to 25 be had to the following description and the accompanying drawing, in which:

Figure 1 is a perspective view of my improved collar attachment, Fig. 2 is a front elevation thereof with parts in section, and 30 Fig. 3 is a side elevation with parts in section.

Corresponding and like parts are referred to in the following description and indicated in all the views of the drawing by the 35 same reference characters.

Referring to the drawing the numeral 1 designates two spaced suspension straps of strips of canvas or the like which are designed to extend over the horse's neck, one 40 in front of the collar and one in the rear of the same, the ends of said straps being secured to the ends of two side bars 2 and serving to suspend the latter contiguous to the shoulders of the horse.

45 The side bars 2 are formed in their ends with longitudinal slots 3 through which the ends of the straps 1 pass, and each of said suspension straps is constructed in two sections, one of which is longer than the other 50 and is provided at its end with a buckle 4 arranged for engagement with the shorter section to adjustably secure together the sec-

tions of the strap at one side of the horse's neck, so that the buckle will not chafe the same.

55 The side bars 2 are designed to be suspended above the hame tugs of the hames of the collar, and are bent oppositely and outwardly intermediate of their ends to fit the contour of the collar and thus cause the ends 60 of the suspension straps to lie flat against the horse's neck, and increase the bearing surfaces of said straps. Secured to the middle points of these side bars are two attaching straps 5, said straps preferably passing 65 through longitudinal slots 6 formed near the middle of the side bars. These attaching straps 5 are provided with buckles 7 so that they can be buckled through longitudinal slots 8 formed in the shanks of the hame 70 tugs 9 in front of the hooks proper 10, the attaching straps being pulled tight enough to raise the collar sufficiently to prevent the withers from resting on the horse's neck.

75 The shanks of the hame tugs 9 are pivotally secured at their forward extremities to the hames, in the usual manner, and it is to be observed that in addition to their functions above noted, the attaching straps 5 passed through the slots 8 serve to hold the 80 hame tugs close against the collar, and prevent them from swinging outwardly when the traces are disengaged therefrom.

85 From the above description in connection with the accompanying drawing, the use of my improved collar pad is obvious.

It is to be particularly noted, by referring to Fig. 3, that the suspension straps 1 pass across the inside of the bars 2, so as to be interposed between the ends of the same and the horse's hide and prevent any possible chafing thereof, while the attaching straps 5 extend from the outside of the bars, so as not to be arranged between the same and the collar, and thus permit the side bars to be 95 held close against the latter.

Having thus described the invention, what I claim is:

100 The combination with a collar provided on opposite sides with hame tugs embodying hooks proper and shanks arranged at the forward ends of the hooks proper and pivotally connected to the collar and formed with longitudinal slots, of an attachment of

the character described, comprising suspension straps designed to extend across a horse's neck, one in front of and the other in the rear of the collar, side bars to the ends 5 of which the suspension straps are secured to support the side bars above the hame tugs, and attaching straps connected to the side bars intermediate of the ends thereof and

buckled through the slots in the hame tugs, as and for the purpose specified.

In testimony whereof I affix my signature in presence of two witnesses.

CHARLES R. CURRENT. [L. S.]
